[57] CLAIM

The ornamental design for a surgical skin stapler, as shown in the accompanying drawings.

DESCRIPTION

FIG. 1 is a perspective view of a surgical skin stapler showing our new design;

FIG. 2 is a side elevational view thereof;

FIG. 3 is a top plan view thereof;

FIG. 4 is a bottom plan view thereof;

FIG. 5 is an end elevational view thereof;

FIG. 6 is an end elevational view opposite that shown in FIG. 5.

Fig. 2.
